[57] CLAIM

The ornamental design for a combined handbag and detachable fitted clutch, as shown and described.

DESCRIPTION

FIG. 1 is a front perspective view of a combined handbag and detachable fitted clutch, showing my new design;

FIG. 2 is a right side elevational view, the opposite side being a mirror image thereof;

FIG. 3 is a front perspective view with the handbag flap open;

FIG. 4 is a front perspective view showing the clutch partially removed; and

FIG. 5 is a rear perspective view thereof in closed condition.
